United States Patent Office.

IMLAY B. VIETS, OF NEW BRITAIN, CONNECTICUT.

Letters Patent No. 2,600, dated March 19, 1867.

DESIGN FOR AN AXE HANDLE.

The Schedule referred to in these Letters Patent and making part of the same.

TO ALL WHOM IT MAY CONCERN:

Be it known that I, IMLAY B. VIETS, of New Britain, county of Hartford, and State of Connecticut, have invented or produced a new and original Design for an Axe Helve; and I do hereby declare that the following is a full and exact description of the same, referring to the photographic views, in which the same letters indicate like parts in each of the figures.

In the accompanying illustrations A is a section of an axe helve. B is a protuberance configuration formed on the helve. The helve, with the protuberance configuration, combine to produce a new and useful pattern or design for an axe helve.

What I claim and desire to secure by Letters Patent, is—

The pattern or design for an axe helve, substantially as illustrated and described.
